INVENTOR:
Agnes M. Dillon,
By Almon Hall, Atty.

UNITED STATES PATENT OFFICE.

AGNES M. DILLON, OF TOLEDO, OHIO.

BOOK-HOLD.

1,199,058.

Specification of Letters Patent. Patented Sept. 26, 1916.

Application filed January 3, 1916. Serial No. 69,786.

To all whom it may concern:

Be it known that I, AGNES M. DILLON, a citizen of the United States, residing at Toledo, in the county of Lucas and State of Ohio, have invented certain new and useful Improvements in Book-Holds; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The wear and tear of books,—especially school books and books of circulating libraries,—are due principally to the contact and abrasion of the hand,—sometimes moist,—which holds and presses against the leaves of the open book near their lower inner corners and which also presses against the back and lids or covers of the book at and near their bottom. The economical and sanitary objections to books thus worn and soiled are manifest, particularly in public schools where the books are furnished and owned by the public and which are used by successive pupils until worn out.

The object of the present invention is to overcome—largely—the difficulties and objections here indicated by furnishing an individual book-hold which protects the inside and the outside of the book against contact with the hand which holds the book; which may without cutting or pasting be readily attached to and detached from the book; which is adjustable to any ordinary book, and which when in place serves as a convenient book-mark.

To these ends my invention consists of the devices hereinafter described, and shown and illustrated in the accompanying drawings, in which—

Figure 1 is a perspective view of a closed book provided with my device; Fig. 2, a like view of a book with one of its lids thrown open to show the manner of retaining in place the back-piece hereinafter referred to; Fig. 3, a view of the lower part of a book, open and showing in operative position the thumb-piece hereinafter referred to; Fig. 4, a plan-view of the blank for said back-piece, and Fig. 5, a plan-view of the blank for said thumb-piece together with the connecting adjusting cord herein-after referred to.

Like numerals of reference indicate like parts throughout the drawings.

In the drawings, in Fig. 4, is represented a blank 1, which may be of any suitable outline, cut through on lines 2 and adapted to be bent or folded on lines 3—4—5. The cuts 2 form at one end of the blank three flaps, 6—6—7.

In Fig. 5 is illustrated a blank 8, which may be of any suitable outline, adapted to be folded or doubled on line 9. The two blanks 1 and 8 may be formed of any suitable material, preferably thick tough smooth paper. The blank 8 is provided with perforations 10 through which is looped a cord 11. This loop may be lengthened or shortened at will by sliding the knot 12 at the end of the loop along the cord. The point of the blank 1 is folded down on line 5 so that the two perforations 13 coincide. The end of the cord 11 opposite the loop is tied in these perforations or otherwise connected to the end of the piece 1. The flap 7 is folded over on line 3. The bottom of the back of the book is placed upon this folded flap. Flaps 6 are next folded inwardly over the bottom margins of the lids of the book at opposite sides of the back. The book may now be closed and the back-piece 1 will fit against the lower part of the back and lids and will be held securely in place by means of the flaps 6 clasped between the lids and the leaves of the book. Now the back of the book and the sides in the vicinity of the back are smoothly and effectually covered by the back-piece 1. The cord 11, which has been adjusted to proper length by means of the knot 12, is next brought up over the back of the book and down between the leaves of the book at the desired place. The folded thumb-piece 8 being placed so that its straight lower edge coincides with the lower edges of the leaves and so that the thumb-piece falls equally upon the exposed pages, the device is ready for use.

It will now be seen that a hand grasping the book in the ordinary manner will not touch the book itself, but the thumb will rest upon the part 8 and the fingers will rest against the part 1, these parts serving as shields which protect the book in the manner and with the advantages above indicated.

While I have herein shown and described a specific embodiment of my device

for protecting books, as well as their readers, by means of individual removable book-holds, it must be understood that the invention is not limited to the mere details here set forth, since,—without departing from the spirit of my invention,—modifications of and deviations from this illustrative form will now suggest themselves.

It will be understood of course that by the terms "top", "bottom", "upper" and "lower" parts of a book is meant these parts of the book when the book is in reading position.

What I claim as my invention and desire to secure by Letters Patent, is—

1. In a device of the character described, a protector which forms a cover for the lower part of the back and the adjacent corners of the lids of a book, means for engaging said cover in operative position upon the book, a shield for the lower adjacent inner corners of opposed leaves of such book, and a cord which connects said protector and shield.

2. In a device of the described character, a protector for the lower part of the back and the adjacent corners of the lids of a book, means for detachably securing such protector in operative position, combined with a shield for the adjacent lower inner

corners of the leaves of such book, a cord connecting the protector and the shield, and means for the adjustment of the length of the cord.

3. In a device of the described character, a member forming a protector for the lower end of the back and the adjacent inner corners of the sides of a book, and means for detachably securing said protector in operative position, combined with a shield for the adjacent lower inner corners of the leaves of such book, and a device which connects the protector and the shield, and means for the adjustment of the shield relatively to the book and to said protector.

4. In a device of the described character, a member which forms a protector adapted to fit the lower part of the back and lids of a book, said member having flaps for engagement with the lower margins of such lids, a shield for the lower adjacent portions of the leaves of such book, and a flexible extensible connection between such protector and said shield.

In testimony whereof I affix my signature in presence of two witnesses.

AGNES M. DILLON.
